UNITED STATES PATENT OFFICE.

RUDD HARDESTY, OF DENVER, COLORADO.

SIGN AND PROCESS OF MAKING THE SAME.

Specification of Letters Patent. Patented Oct. 16, 1917.

1,243,164.

Application filed March 17, 1916. Serial No. 34,761.

To all whom it may concern:

Be it known that I, RUDD HARDESTY, a citizen of the United States, and a resident of Denver, in the county of Denver and the State of Colorado, have invented a certain new and useful Improvement in Signs and Processes of Making the Same, of which the following is a full, clear, and exact description.

10 My invention is an improvement in signs and in the process of making the same. The object of the invention is the provision of a sign the reading portion of which may be conveniently varied and which shall be substantial in appearance, weather proof, readily legible, of low manufacturing cost, and substantially indestructible—thus rendering it especially adapted for use as street and road markers. To these ends the sign comprises 15 a metallic base plate with die cut metallic letters welded thereto, the whole being suitably treated to protect all the parts from the action of the atmosphere and to render the lettering readily legible on a suitably contrasting background. Further and more detailed objects and advantages of my invention will later appear from this specification.

In the single sheet of drawings accompanying this application and forming a part 20 hereof—

Figure 1 is a plan or face view of a sign made according to my invention;

Fig. 2 is a section on the line A—B, Fig. 1, through a partly finished sign in which 25 galvanized letters have been used;

Fig. 3 is a section similar to Fig. 2 of a sign in which untreated metallic letters have been used; and

Fig. 4 is a section similar to Fig. 3 through 30 a finished sign.

Referring to the drawings, let 5 indicate the metallic plate which is to form the base plate of the sign. On this base plate, which preferably is of black iron, the letters which 35 are to form the sign are assembled and held in proper alignment by any desired means, not shown. These letters are die cut and may be of galvanized iron as indicated in Fig. 2; or they may be of untreated metal, 40 preferably black iron, as indicated in Figs. 3 and 4. The letters are then welded securely to the base plate by the electric spot welding process; the flat electrode being applied to the letter surface and the pointed or 45 sharp one to the rear of the base plate. The surface of the letter is thus not marred and,

in case that galvanized metal letters are employed, the galvanizing is not even destroyed. Indentations 6 made by the flow of the metal appear on the rear of the base 50 plate but these are in such position as not to be visible on the reading side of the sign and therefore do not mar its appearance. The number of points of welding required is determined by the size and shape of the 55 letters to be joined but a sufficient number of points are selected so that the letters are very closely joined to the base plate. This may be seen by cutting sections such as those shown in Figs. 2, 3, and 4; in which sections, cut through a partially finished sign, the line of demarcation between the plate and letters is scarcely distinguishable even at points remote from the welding spots. Tests for the removal of such letters will 60 show that even with a tool it is scarcely possible to cut them off and that when they do come a portion of the plate has been torn out or a part of the letter torn off. It will therefore be clear that the union between the 65 base plate and letters is so close as to render corrosive action of the atmosphere between them substantially impossible.

After the letters or other insignia which the sign is to bear are secured in place the entire sign is dipped in enamel and baked. If, due to any bends or flaws in the plate or letters, the contact between them is not perfect this coat of enamel 7 will effectually 70 close any openings through which moisture 75 might enter and will render rusting or electrolysis impossible.

The last step in the process is the coating of the letter faces with a sizing, allowing 80 this to become tacky and then applying some metallic bronze 8 thereto—preferably aluminum bronze. When this last coat is thoroughly dry there is produced a bright letter 85 on the markedly contrasting background of enamel—which latter is preferably black.

The die cut letters may conveniently be carried in stock in the various sizes required and signs, such as street markers, requiring an extensive variation in lettering may be 90 readily made—thus constituting a great improvement over cast iron signs where new molds must be made for every variation. My sign, in which the letters are practically 95 integral with the plate and therefore impossible of being torn or broken therefrom, also is obviously an improvement over similar devices in which letters are screwed or 100

riveted to the base plate. The sign described in this application is also superior to an embossed sign in that the latter must be made of relatively thin metal and therefore lacks the substantial qualities of a sign made by my method—in which the base plate employed may be of any desired thickness to give the desired rigidity and permanence.

5 10 Having thus described my invention what I claim and desire to secure by Letters Patent is:—

15 1. The herein described process of sign making, consisting in assembling metallic letters in proper relation on a metallic plate, electrically spot welding the letters and plate firmly together, dipping the lettered plate in an enameling bath, baking the enamel, and applying a contrasting metallic 20 paint to the faces of the letters.

2. As an article of manufacture, a sign comprising a metallic base plate, die cut metallic letters electrically spot welded thereto,

and a coating of enamel covering the unlettered surface of the base plate and the exposed surface of the letters. 25

3. As an article of manufacture, a sign consisting of a metallic base plate, die cut metallic letters electrically spot welded thereto, a coating of enamel applied to the 30 unlettered surface of the base plate and the exposed surface of the letters, and a metallic paint applied to the enameled faces of the letters.

4. As a new article of manufacture, a sign 35 comprising a metal base plate and relatively thin flat metal characters spot-welded thereto, the exposed surface of said characters being unmarred by the weld, in combination with a continuous adherent layer of enamel 40 covering the exposed surface of said plate and characters.

In testimony whereof I have hereunto affixed my signature.

RUDD HARDESTY.
